BOTTOM FILLING EXTRUDING MACHINE

Percy White, Leicester, England, assignor to
 United Shoe Machinery Corporation, Flemington, N. J., a corporation of New Jersey

Application February 28, 1948, Serial No. 11,952
 In Great Britain March 26, 1947

10 Claims. (Cl. 12—79.6)

1

This invention relates to machines for filling shoe bottom cavities, and more particularly to improvements in bottom filling machines of the type described in United States application Serial No. 746,926, filed May 9, 1947, in the names of C. M. Bagshaw, F. C. Choice, and J. W. Pratt and also in the British application No. 17,141, filed June 6, 1946.

In many shoe manufacturing processes, before the attachment of an outsole and after the upper has been lasted over an insole, there is a shoe-bottom cavity bounded by the inner edge of the overlasted upper. In Goodyear welt shoes, for example, this cavity lies within the inseam in the forepart, or the forepart and shank, and this cavity is usually filled with a soft resilient material to present a smooth surface and requisite backing for the outsole. It is customary to fill the cavity flush with the top of the inseam and the material used is a filling composition such, for example, as a mixture of ground cork and a binder which may or may not be thermoplastic but customarily requires heating to permit spreading of the same.

The machine described in the applications referred to above includes a matrix box arranged to overlie the forepart of a shoe which is pressed upwardly against a thin metal diaphragm or matrix forming the lower wall of the matrix box. This matrix is sufficiently flexible to enable it to accommodate itself to the varying curvatures along and across the bottoms of different shoes. This diaphragm or matrix, by contact with the upper edge of the insole lip present on a welted shoe, forms a closure for the upper side of the shoe bottom cavity as a shoe is presented to the machine bottom upward. The machine also includes a reciprocating plunger device for extruding plastic bottom filling material through a short metal tube which passes downwardly through a central portion of the matrix or diaphragm and opens into the cavity in the shoe bottom. The speed of reciprocation of the plunger is low enough to ensure avoidance of undue compression of the bottom filling material but is adequate to ensure that the material will find its way into all portions of the cavity.

In order to ensure that the plunger may, on a single stroke, supply sufficient bottom filling composition to the cavity to fill the latter completely, the plunger has associated with it a hollow pick up sleeve which is caused to travel ahead of the plunger through a mass of material in an agitating drum therefor, and in so doing, to carry an adequate amount of filling composition

2

with it. Continued advance of the plunger expels the material from the sleeve and through the short metal tube in the matrix which leads to the cavity in the shoe bottom.

With a view to preventing an excessive amount of material being applied to the cavity in the shoe bottom by the plunger, the machine of the aforesaid applications is provided with a by-pass valve positioned just above the matrix, which the operator may operate when he considers that sufficient material has been applied to the cavity in the shoe bottom and the mechanism acts first to cut off further entry of material into the short metal tube in the matrix box and to disconnect the plunger from the power means for moving it. The by-pass valve is then opened to return excess material to the agitating drum and recouple the plunger to said power means so that such material carried forward by the further 10 plunger movement will return directly to the drum without passing into the shoe bottom cavity. The machine also includes convenient means for supporting a shoe in firm contact with the matrix during a bottom filling operation 15 thereon and automatic means for locking the shoe against movement out of proper position during the operation and for releasing it for removal from the machine at the conclusion of the operation.

20 In the operation of the machine as above described the shoe being worked upon is subjected to a necessary upward movement into sealing relation with the matrix or diaphragm. Such upward movement is essential in that machine in 25 order to secure an effective seal between the matrix and the shoe bottom, such seal requiring considerable pressure. Upon release of the shoe from the machine, some bottom filling composition is drawn away from the lower end of the 30 short metal tube in the matrix box and forms an unwarranted protuberance in the central portion of the shoe bottom. This protuberance entails an additional step to be performed for it must be pressed down to the level of the bottom filling 35 material in the cavity before further operations 40 on the shoe may be carried out.

The object of the present invention is to provide improved means for effecting a seal between the shoe bottom and the matrix and to avoid the 45 formation of a protuberance of excess bottom filler composition on the shoe bottom.

To the above ends, one feature of the invention comprises a cam operated mechanism for pressing the margin of a matrix of thin flexible 50 metal into effective sealing relation with the bot-

is by a link 17, lever 18, a spring 19 and other parts shown in the applications referred to.

Like the machine described in the applications referred to, the machine herein illustrated is provided with a matrix box 20 which, however, is of a modified construction. A channel 22 (Fig. 4) extends forwardly and downwardly from the by-pass valve 16 to a short metal tube 24 communicating with the under side of the diaphragm or matrix 26 of the matrix box 20. The by-pass valve 16, passage 22 and other parts to be described are located in a head casting 28 suitably bolted to a front portion of the machine.

Where contact is made with the matrix 26, the exterior wall of the matrix box 20 corresponds, in outline, to the shape of the forepart of an exceptionally wide shoe. The matrix box comprises the thin flexible metal matrix or diaphragm 26 having a width of about five and one-half inches and a length of about six inches, which matrix forms the lower or enclosing wall of the box and is of sufficient size to close the cavity in the bottom of any shoe to be treated. The short metal tube 24 passes downwardly through the upper wall 30 of the box 20 and serves to clamp the matrix 26 in place against a central backing plate 32 disposed above it, thereby providing a duct whereby the bottom filling material may pass through the matrix box and matrix 26 into the cavity of a shoe bottom presented to the machine.

The backing plate 32 is formed as a part of an upper wall 30 and is similar in outline to the side wall of the matrix box 20 although its outline is much smaller in width and length, its width being approximately one and one-half inches and its length approximately four and one-half inches. The heelward end of the backing plate 32 approaches closer to the heelward end of the matrix box 20 than does its toeward end to the toeward end of the matrix box (see Fig. 4). The backing plate 32 has an inwardly extending groove 36 (Figs. 4 and 10) running around its periphery near its lower edge.

The upper wall 30 of the box 20 is provided on its outer surface with four internally threaded upstanding bosses 40 (Figs. 5 and 9) for receiving vertically disposed and threaded studs 42 (Figs. 3, 4 and 11) by which it is secured in fixed position on the head casting 28 of the machine, the periphery of the matrix 26 lying in a substantially horizontal plane with its toe end pointing toward the rear of the machine. A depending U or V-shaped wall 44 is fixed to the upper wall 30 of the matrix box 20 and extends continuously along the sides and toe end portions thereof, but not across the heelward end portion of the wall 30. A series of eight vertical holes 50 (Fig. 5) are formed in the depending wall 44 along its side portions, there being four holes 50 in each side portion which holes are equally spaced. The holes 50 extend downwardly through the wall 44 (Fig. 6). Two similar holes 52 (Fig. 5) are made through the toeward portion of the depending wall 44, being spaced on each side of the median line extending lengthwise of the matrix box 20. A tension spring 54 (Fig. 6) is disposed within each of these ten holes and is supported at its upper end by a cross pin 56 at the upper end of the hole and resting within a slot (not shown) formed in the plate or wall 30. The lower end of each spring 54 is connected to that portion of the matrix 26 which lies below the spring, which portion is thereby pulled upwardly into contact with the lower edge of the depending wall 44 by

tom of a shoe preliminarily placed in position to be operated upon. A further feature comprises a cut-off valve which supplements the control of the flow of the bottom filling composition provided by a by-pass valve and which cut-off valve functions in a plane which is approximately that of the matrix.

These and other features of the invention, including certain details of construction and combinations of parts, will be described as embodied in an illustrated machine and pointed out in the appended claims.

In the accompanying drawings,

Fig. 1 is a view in front elevation of a machine embodying the features of the present invention;

Fig. 2 is a view in side elevation, partly broken away and looking from the right side of the machine illustrated in Fig. 1, and drawn to a larger scale;

Fig. 3 is a view in front elevation on an enlarged scale of a portion of the apparatus shown in Fig. 1, a section being taken through the matrix box and the cut-off valve;

Fig. 7 is a sectional view taken along the line VII—VII of Fig. 5;

Fig. 8 is a bottom view of the matrix or diaphragm of Figs. 4 and 5;

Fig. 9 is a front view of the matrix box;

Fig. 10 is a perspective view showing the bottom of the matrix box with the matrix or diaphragm and other parts removed for the purpose of illustration; and

Fig. 11 is a plan view of the mechanism shown in Fig. 4.

The illustrated machine in which the present invention is embodied comprises a vertical casing and all the interior working parts including an agitating drum, power drive details and controls as described in the applications heretofore referred to together with a modified form of matrix box and improved controls for the flexing of the matrix and flow of the bottom filling composition at the matrix.

Mounted on the base of the casing 10 is a treadle 12, as shown in the earlier applications, which treadle is utilized for actuating shoe clamping pads 14 and subsequently tripping a clutch for starting rotation of a driving motor connected to a source of electrical energy. The parts in the casing 10 are not shown in the drawings as they form no part of the present invention, but it may be stated in a few words, that the motor drives a rotating or agitating drum containing bottom filling composition supplied to it from a hopper, and a plunger or piston together with an associated sleeve extrudes bottom filling material from the drum through a by-pass valve 16 (Fig. 4) to the cavity in the bottom of a shoe 2 (Fig. 2). The by-pass valve 16 (the purpose of which is to allow bottom filling material to be supplied to the cavity in a shoe bottom or alternatively to allow the material to be fed back to the rotating drum according to the position of the valve) may be rotated to cut off the supply of bottom filling material when a sufficient amount has been supplied to the shoe bottom cavity and such rotation also causes the shoe clamping pads 14 partially to release a shoe. The connections between the valve 16 and the pads

a screw 60 which passes through the matrix 26 and which is threaded on to the tension spring 54.

In each of the two opposite side portions of the depending wall 44 which are located toward the heelward end of the matrix box 20, a blind hole 62 (Figs. 5 and 7) is made, extending downwardly from the upper edge of the depending wall for at least three-quarters of the depth of that wall and the wall in the region of and about the blind hole is cut to form an opening 63, the 10 depth of the part cut away being about one-half that of the wall (Fig. 7). A similar wall opening 63 (Fig. 7) and blind hole 62 (Fig. 5) is made at the most toeward part of the wall 44 and a compression spring 64 (Fig. 7) is seated within each of the three blind holes 62 for a purpose later to be described.

A series of fingers 66 (Fig. 10) is arranged in such a way that they extend radially and outwardly from the backing plate 32, the inner ends of these fingers 66, which are reduced as to their vertical dimensions, extending within the groove 36 in the backing plate and being capable of a small amount of up-and-down and in-and-out movement therein. Each finger comprises a thin wedge shaped, plate-like member which, when viewed from its side, presents a lower surface at that edge more remote from the upper wall 30 of the box which is inwardly and upwardly inclined. Thus, in cooperation with the flat lower surface of the backing plate 32, the inclined edges of the fingers 66 (which actually lie in contact with the upper surface of the matrix 26) provide a concave contour corresponding with the convex contour which normally exists along and across the bottom of a shoe forepart. At their outer ends the fingers 66 are provided with short ears 68 (Fig. 4) extending outwardly from their upper portions and lying substantially in the same horizontal plane as their reduced inner ends 36. These ears 68 are constrained against excessive downward movement by a shoulder 70 formed on the lower end of the aforesaid depending wall 44. It is to be understood, therefore, that the outer ends of the fingers 66 may rock upwardly or downwardly in relation to their inner ends which latter are prevented from vertical movement by the groove 36 in the backing plate 32. Upward or downward movement of the outer ends of the fingers 66 will result in corresponding movement of the outer margin of the matrix or diaphragm 26. The fingers 66 are preferably arranged in groups of four (Fig. 10), the fingers of each group lying side by side in contacting relation with each other and being so retained by guide pins 70 (Fig. 10) projecting downwardly from the upper wall 30 of the box 20 and lying close to the outermost fingers of each group near their outer ends. Conveniently there are twelve such groups of fingers arranged along each side portion of the box. The outer ends of the two adjacent groups at the toe end of the matrix box are spaced slightly more than an inch apart and make only a small angle with the median line extending lengthwise of the box while the outer ends of the outermost heelward pair of the groups lie just heelwardly of the heelward end of the backing plate 32. The fingers of these two last-mentioned groups extend inwardly and somewhat toewardly in directions which will lie more or less perpendicularly to those side portions of a shoe presented to the machine which lie toward the toeward end of the waist of the shoe. The separation of the groups in the region of the toe end of the box 20

is equal approximately to the width of the groups themselves but this separation is progressively decreased in width toward the heelward end of the box, being equal, in that region, to about one-half the width of the group. In the gap between the most toeward pair of groups of fingers there is provided a single finger 72 which is about three-quarters of an inch in width at the outer side and which tapers to about one-third of that width where it adjoins the backing plate 32. The shape of this single finger as viewed in a vertical plane is generally similar to that of the other fingers before mentioned. The groups of fingers 66 and the single finger 72, each supports a spring 74 seating within a recess formed in the upper surface of a group of fingers or the single finger.

There is disposed within the matrix box 20 about the backing plate 32 and above the upper ends of the springs just referred to, a metal plate 80 which normally is thrust upwardly against the lower face of the wall 30 by the three compression springs 64 which are seated within the blind holes formed in the wall 44. This plate 80 has approximately the same shape as the matrix box, when looked at from above, and the inner edge of the plate closely embraces the metal backing plate 32 while the outer edge thereof is closely embraced by the depending wall 44, the three compression springs 64 bearing against suitable projections 82 (Fig. 5 and 7) on the margin of the plate 80 which fit within the wall openings 63. The upper ends of those springs 74 which seat within the recesses provided in the various groups of fingers bear against the under side of the plate 80 inwardly of its outer margin. Downward movement of the plate 80 (by means to be described), against the thrust of the compression springs 64, will be transmitted to the outer end portions of the fingers 66 and finger 72 and hence to the outer margin of the matrix 26 through the springs 74 interposed between the plate and the fingers, thereby causing the margin of the matrix 26 to flex and accommodate itself to variations in the height of the insole lip present on a welt shoe then held fixedly against the matrix. Adequate contact is thereby made with the insole lip all along the sides and around the toe end of the shoe bottom cavity to form an effective seal.

The central portion of the diaphragm 26 is secured to the backing plate 32 and for this purpose the short, downwardly extending tube 24 has a flared head for clamping the diaphragm 26 to the under side of the backing plate 32. This detail is as described in the patent applications referred to. A hexagonal nut 90 is threaded upon the top end of the tube 24 and a recess 92 is formed in the top of the wall 30 to receive the nut 90. The tube 24 and the nut 90 serve to maintain the matrix box 20 with its parts in assembled relation as well as providing a passage for the flow of bottom filling composition through the matrix and into the shoe bottom cavity.

The matrix 26 comprises four overlapping plates of very thin resilient steel which, when assembled together, have a size and outline similar to that of the matrix box depending wall 44. One of these plates 94 (Fig. 8) is adapted to engage the toe portion of the bottom of a shoe offered to the machine and is approximately V-shaped as seen in plan, the apex of the plate 94 completely surrounding the fluid conducting tube 24, above the head on the latter, the plate extending toewardly to the extreme toe end of the matrix box where its width is at least about two

inches. This plate is held yieldingly against the lower surface of the depending wall 44 by two springs 54 acting through screws 60 the springs being located within holes 50 in that wall as previously described. Two other plates 96 and 98 are arranged to extend from the side portions of this toe end plate 94 along the opposite sides of the matrix box and these two plates are upheld yieldingly against the wall 44 by eight springs 54 acting through screws 60, the springs being located in holes 50 spaced apart in the wall 44, two of the holes 50, as shown, being closed to the heelward end of the box. The plates 96 and 98 have portions which overlap the side margins of the toe end plate 94. Each plate 96 and 98 is notched to fit halfway around the tube 24. These side plates do not, however, extend completely across the width of the box at its heelward end but rather present a somewhat V-shaped gap between them in that region, the wider part of the gap lying below the heelward edge of the box. This heelward gap is covered by a fourth plate 100 which has a portion surrounding the tube 24 and is of a shape corresponding to that of the gap but somewhat larger so as to overlap the adjacent marginal portions of the side plates 96 and 98. The overlapping marginal portions of the four plates are flexibly attached to each other at 95 as by riveting, thus presenting a unitary diaphragm or matrix the various portions of which may readily tilt and yield heightwise relatively to each other. There are, of course, no diaphragm fingers 66 above the central portion of the diaphragm at the extreme heelward end of the box and, in order to provide adequate support for the fourth plate 100 against too ready heightwise movement when pressed downwardly against a shoe, this plate 100 has a metal bar 102 secured to the upper face of its heelward margin. It may be spot welded thereto say, at points 104 and 106 (Fig. 8). This bar 102 extends widthwise of the box just beyond the heelward end of the backing plate 32 and a short spring 110 located between its central portion and the under face of the wall 80 normally supports the heelward end of the plate 100 in the desired heightwise relation to the remaining plates but allows it to yield upwardly if necessary. The upper edge of the bar 102 tapers downwardly from the center toward each of its ends and so provides capacity for the bar, and the plate which it supports, to tilt laterally if necessary.

Downward movement of the metal plate 80 and hence of the diaphragm margin, with respect to the walls 30 and 44 of the matrix box is effected by means of four plungers 112 (Fig. 3) which fit within four downwardly extending bores 114 formed in the head casting 28 and which pass through corresponding apertures 116 (Fig. 5) in the wall 30. Two of these bores 114 are disposed toward the toeward end of the matrix box and are equally spaced on each side of the median line extending lengthwise of the box while the other two of these bores 114 are located near the heelward end of the box, these also being equally spaced on each side of the median line but further away therefrom than the two first-mentioned bores 114. The bores extend upwardly in the head casting 28 for the greater part of the height thereof. The bores 114 at the toeward end of the matrix box terminate in a horizontal channel 120 (Fig. 4) made in the head casting and extend completely through the casting and in a direction from side to side thereof. The bores 114 at the heelward end of the matrix box similarly

extend upwardly and they terminate in a similar and parallel horizontal channel 122 (Fig. 4), the two horizontal channels lying in the same horizontal plane and being covered by means of a cover 124 retained in position beneath the heads of bolts 42. Toward the lower end of each bore 114 the diameter thereof is reduced so as to provide a shoulder 126 (Fig. 4) against which a widened part of the associated plunger 112 may bear. When the vertically movable plate 80 is in contact with the under surface of the wall 30 of the matrix box this widened part of each plunger 112 is positioned a short distance above its cooperating shoulder 126 so as to permit downward movement of the plunger. The lower ends of the plungers 112 rest upon the upper surface of the plate 80 and the lower end of each plunger is flat so as to conform with the surface of the plate 80 and the upper end of the plunger is semi-spherical extending partially into its associated hollow channel 120 or 122. A horizontal cam bar 130 (Figs. 3 and 11) extends within and is slideable along each horizontal channel 120 or 122 and has formed on its under surface two arcuate and concave surfaces 132 each arranged to actuate one of the plungers 112 upon movement of the proper cam bar 130. When the movable plate 80 is in contact with the under surface of the wall 30 the semi-spherical end of each plunger 112 bears against the highest point of its cooperating arcuate cam surface 132 and endwise movement of a bar 130 causes two of the plungers 112 to move downwardly. The horizontal cam bars 130 are caused to move simultaneously and thus all four plungers 112 move downwardly together rocking all the groups of fingers 66 and finger 72 downwardly about their inner ends.

Endwise movement of the cam bars 130 is effected by a bell crank lever 140 and a lever 141 (Figs. 3 and 11) fixed to a shaft 142 pivoted on the head casting 28, end portions of a forked arm of each lever 140 and 141 engaging with the cam bars and the end of the arm 143 (Fig. 3) on the bell crank lever 140 being pivotally connected to a downwardly extending link 144 which is connected to a toggle mechanism (hereinafter referred to) by means of a lever 146 and gearing 147.

As fully illustrated and disclosed in the above-mentioned patent applications, the shoe clamping pads 14 are operated by mechanism including a vertically movable bar 148. Vertical movement of this bar is effective to cause the pads 14 to move toward or away from their shoe clamping positions. Vertical movement of the bar is effected by a treadle rod 149 the upper end of which is pivotally connected to the midpoint of a lever 150 which is pivoted at 210 near its forward end, to the lower end of the bar 148 and is upheld at its rearward portion by a relatively strong spring 212. The rearward end of the lever 150 is connected to means 214 for controlling a clutch (not herein shown). The arrangement is such that depression of the treadle 12 connected to the lower end of the treadle rod 149 first causes the shoe clamping pads 14 to move against a shoe and then, when firm contact with the shoe is obtained, resistance to further clamping movement causes the lever 150 to swing reversely about its forward pivot to actuate the clutch control means to start the power operation of the machine.

Also, as in the machine of the above-mentioned patent applications, the bar 148 is connected to a rack 151 positioned so that the teeth thereof

may come into engagement with a pair of pawls (not shown herein). The construction is such as to provide more positive support for the shoe against displacement from the matrix when bottom filler material is being forced into the shoe bottom cavity. To this end a link 216 is pivotally connected (at its front end) to the upper end of a toggle link 218 the lower of which is pivoted on a pin 220 fast in the machine frame. The forward end of toggle link 218 is pivoted to a second toggle link 222, the two occupying a broken relation when the machine is at rest as shown in Fig. 2. The upper end of the link 222 is pivoted to the rear end of a pawl-carrying lever 224 fulcrumed on a fixed pivot pin 226. The forward end of the lever 224 carries a pin 228 on which a pair of substantially vertical pawls (not shown herein) are mounted one beside the other. These pawls are urged by springs to engage the teeth on the rack 151. The arrangement is similar to that of the applications referred to in that a rearward movement of the link 216 straightens the toggle links 218 and 222 connected to the pawl-carrying lever 224 and, by thus thrusting upwardly on the rear end of that lever, pushes the pawls downwardly and moves the rack bar 148 downwardly accompanied by a further inward movement of the shoe engaging pawls 14. The pads are then retained in their further inward positions by the straightened toggle links 218 and 222. The rearward movement of the link 216 is also accompanied by a slow forcing of filler composition into the shoe bottom cavity. The operator causes the valve 16 to rotate when the cavity in the shoe bottom is filled, the operation on the shoe being completed. Rotation of the valve 16 not only cuts off the flow of filling material through the matrix but also releases the shoe for removal from the machine, causing also the completion of the advancing and withdrawing movement of the plunger to its initial retracted position at high speed. The machine then comes to rest with the parts except for the valve 16, in their original positions.

Withdrawal of the pawls from engagement with the rack 151 is caused by movement of the valve 16 to raise the pawls to a more elevated position from that in which they originally engaged the rack bar, and means is provided to swing the pawls away from the rack bar holding them thereafter in withdrawn position. Free'y mounted on the pivot 228 and loosely held on a fixed pin 229 is a lever 230 with a hand pad at its forward end. This lever 230 is arranged to move upwardly with the rack 151 and if a shoe has been improperly clamped by the pads 14 the operator may depress the hand pad and thus manually disengage the pawls from the rack 151 to free the shoe.

In the machine embodying the present invention, a departure has been made from the disclosure of the applications referred to in that lever 224 is now keyed or otherwise fastened to the shaft or pin 226 to rotate therewith and that pin 226 is provided with a bevel gear 232 in mesh with a bevel gear 234 keyed to a shaft 236 upon which lever 146 is affixed. The bevel gears 232 and 234 constitute the gearing 147 already referred to.

The head casting 28 has an electric heating element 152 (Fig. 4) housed within it and an additional horizontal bore 153 is provided at the heelward end of the casting 28 in the event that an additional heating element should be needed for a given specific filler composition. This heat-

ing element 152 is utilized to heat the filling composition during the operation of the machine suitably to soften the same at the extrusion zone.

The matrix box 20 is located in fixed position upon the head casting 28 so that the tube 24 therein through which the filling composition passes to the shoe lies somewhat forwardly of the by-pass valve 16. The channel 22 is formed in the casting 28 to lead from the outlet side of the by-pass valve 16 to a point just about the upper end of the tube 24 (Fig. 4). A vertical bore 154 having an internal diameter equal to that of the tube 24 is formed in the casting 28 directly above the tube 24 and the channel 22 leads into this bore. At its upper end portion, however, the bore 154 is widened so as to provide a shoulder 156. A valve rod 160 is slidably disposed in this bore 154. At its upper end portion the valve rod 160 has a flange 162 received within the widened portion of the bore. A spring 164 is disposed about the valve rod 160, the upper end of the spring bearing against the flange 162 and the lower end bearing against the shoulder 156. The lower end portion of the valve rod 160 is narrowed to form a neck portion 166 and is then gradually widened toward its end. The neck portion 166 is normally located opposite to the passage 22 in the head casting and is so shaped that it offers a minimum of resistance to flow of material issuing from the channel 22 into and through the tube 24. In such normal position the rod 160 does not quite extend throughout the whole length of the tube 24 in the matrix box 20, it in fact terminating a short distance from the restricted bottom opening thereof.

The head casting 28 is rigidly supported on the machine frame by three horizontal bolts passing through ears 162 (Fig. 3) projecting from the back of the casting. Side brackets 164 and 166 are also formed on the head casting 28 and vertical bars 168 and 169 depend therefrom and steady the entire assembly as in the machine of the patent applications referred to.

Engaging the upper end of the valve rod 160 is one end of a substantially horizontal lever 170 (Fig. 3) pivoted on the upper end of the head casting 28. The other end of the lever 170 rests on one arm 172 (Fig. 4) of a bell crank lever pivoted at 173 on a projection from the machine frame. The other arm 174 of the bell crank lever is connected by means of a link 180 (Fig. 2) to a foot treadle 182, a tension spring 183 being provided for upholding the treadle 182 with the parts in the positions shown in Figs. 2, 3 and 4. An abutment 184 on the arm 174 of the bell crank lever is adapted to engage an arm 186 (Fig. 2) of another bell crank lever which actuates the by-pass valve 16 to terminate the flow of bottom filling material therethrough and to cause surplus material to flow back into the drum of the machine. Consequently depression of the treadle 182 causes downward movement of the arm 174 thereby cutting off the supply of bottom filling material to the tube 24 in the matrix box and at 60 or about the same time causes downward movement of the valve rod 160 and brings its lower end into seating engagement with an inturned flange 190 (Fig. 4) on the lower end of the tube 24 to close the tube and prevent whatever bottom filling material then remains in the tube from being drawn out of it as the operator withdraws the shoe from the machine after the conclusion of a bottom filling operating.

To enable the extruding or cut-off valve 16 to be operated at the proper time during the opera-

tive cycle of the machine for a given shoe, mechanism described in the applications referred to is employed. This mechanism includes a rod 200 which is fixed to, rotatable with, and in axial alignment with the valve 16, a block 501 (Figs. 1 and 2), a valve controlling member or lever 503 (Fig. 2), the rod 17, spring 19, lever 18 (the last three elements already being mentioned), a horizontal rod 519 and an upwardly extending arm 523. The details and operation of these elements are as described in the applications referred to.

The procedure followed in filling the cavity in the bottom of a welt shoe with the aid of the illustrated machine will now be described. Assuming the machine to be in a cold condition the operator will first switch on the electric power to the driving motor of the machine and to the electric heating elements thereof. He will allow the drum containing the cork and binder composition to rotate and the machine to heat up for a sufficient period of time to insure that the material in the agitating drum has reached a smooth and fluent condition free from unbroken lumps.

The operator takes a shoe and, assuming all necessary preparatory operations, including the inseam trimming operation, have been performed, presents it bottom upward and with its toe portion extending away from him, beneath the central portion of the matrix 26. The operator then places the shoe bottom in firm contact with the matrix 26. At this point, however, a tight seal will seldom be provided as the upper edge of the insole rib is usually somewhat rough and slightly undulating as a result of the previous inseam trimming operation. The mere placing of the shoe against the diaphragm 26 by the operator cannot be assumed effectively to seal the cavity completely against the possibility of filling material leaking over the top of the insole rib and finding its way to adjacent parts of the shoe.

With the shoe held against the diaphragm or matrix 26 the operator will depress the treadle 12 which first causes the shoe supporting pads 14 to grip the shoe at opposite side portions thereof and support it against the matrix 26 and secondly, it subsequently trips a clutch to start the machine into power operation (all of which is described in the applications above referred to).

Early in the power operation, the shoe supporting pads 14 are thrust harder against the shoe by means of the toggle mechanism (levers 218 and 222) and are locked in position thus preventing movement of the shoe upwardly or downwardly. At, or about the same time, the horizontal cam bars 130 (which form a part of the present invention) are automatically drawn along their associated horizontal channels by means of the operation of the aforesaid toggle mechanism, gearing 141 (including bevel gears 232 and 234) and levers 140, 144 and 146. The four plungers 112 are forced downwardly and simultaneously within their bores 114 for a short distance. As a consequence the plate 80 moves downwardly and, through the operation of the spring 74, will press the fingers 66 against the diaphragm or matrix 26 and rock the fingers about their inner ends. The margin of the matrix 26 will therefore move downwardly compressing the inseam materials, including the insole lip and will conform to the heightwise curvatures of the inseam materials along the sides and around the toe end of the shoe thus effectively sealing the cavity in the shoe bottom. The amount of downward movement of any part of the matrix 26 will be determined by

the size of whatever gap exists between that part of the matrix 26 and the inseam materials, but it will be appreciated that all parts of the diaphragm margin will move down slightly away from the rim or depending wall 44 of the matrix box 20 since downward movement of the plungers 112 will increase the pressure of the diaphragm or matrix 26 against the inseam materials and thereby increase the sealing pressure.

10 While downward movement of the four plungers 112 is occurring, the plunger and its sleeve (not shown herein), for forcing the flow of the bottom filling composition, will be advancing through the drum of bottom filling material and 15 the treadle 182 will be held in its uppermost position by the spring 183. After downward movement of the plungers 112 has ceased and the matrix has consequently been pressed against the inseam materials, bottom filling material will 20 have reached and been extruded through the open by-pass valve 16 and by the raised neck portion 165 so as to allow the extruded material to flow into the shoe bottom cavity. Continued flow of the material will cause it to flow widthwise and lengthwise throughout the shoe bottom cavity until it emerges beneath the heelward end of the matrix 26 near the waist of the shoe. This 25 emergence will be slight but sufficient to be noticed by the operator and will indicate to him that the cavity has been filled. He will then 30 depress the treadle 182 and cause the by-pass valve 16 to rotate and cut off the supply of bottom filling material to the cavity and at the same time will seat the end of valve rod 160 against the lip 198. 35 The act of rotating the valve 16 (by depression of the treadle 182 and consequent rotation of the lever 186) not only will cause surplus bottom filling material to flow back into the drum of the machine and eliminate any protuberance of 40 bottom filling material on the shoe but will also cause the shoe supporting pads 14 partially to release the shoe and the cam bars 130 to move and allow upward movement of the four plungers 112, thereby allowing the margin of the diaphragm 45 or matrix 26 to be drawn up against the wall 44 of the matrix box by the springs 54.

Having thus described my invention, what I claim as new and desire to secure by Letters Patent of the United States is:

- 50 1. A machine for filling a cavity in the bottom of a shoe including a matrix of sufficient size to close said cavity, said matrix having a passage for the flow of filling composition, means for holding a shoe in position to be operated upon, and means for moving said matrix into firm engagement with the bottom of said shoe and for increasing the pressure of said matrix on said shoe bottom to seal said cavity.
- 60 2. A machine for filling a cavity on the bottom of a shoe including a matrix of sufficient size to close said cavity, said matrix having a fixed central portion and a flexible margin, said fixed central portion being provided with a passage for the flow of filling composition, means for holding a shoe in position to be operated upon, and means for moving the flexible margin of said matrix toward and into engagement with the bottom of said shoe and for increasing the engagement pressure to seal said cavity.
- 65 3. A machine for filling a cavity in the bottom of a shoe including a matrix of sufficient size to close said cavity, said matrix having a flexible working face of spring sheet metal and a fixed central portion with a passage for the flow of filling composition, a number of fingers contact-

ing said sheet metal and extending from the central fixed portion, means for holding a shoe in position to be operated upon, and means to impart motion to the spring sheet metal with the aid of said fingers to press said sheet metal toward and into engagement with the said shoe bottom to seal said cavity.

4. A machine for filling a cavity in the bottom of a shoe including a matrix of sufficient size to close said cavity, said matrix having a passage for the flow of filling composition, means for holding a shoe in position to be operated upon, and cam mechanism for pressing the margin of said matrix against said shoe bottom to seal the said cavity.

5. A machine for filling a cavity in the bottom of a shoe including a matrix of sufficient size to close said cavity, said matrix being composed of sheet metal and a fixed central portion with a passage for the flow of filling composition, a valve in said passage with a seat approximately in the plane of said matrix, means for holding a shoe in position to be operated upon, and means for pressing the sheet metal of said matrix toward and against said shoe bottom to seal said cavity.

6. A machine for filling a cavity in the bottom of a shoe including a matrix of sufficient size to close said cavity, said matrix having a passage for the flow of filling composition, a cut-off valve in said passage with a seat approximately in the plane of said matrix, a by-pass valve above said cut-off valve for returning unused composition introduced under pressure to its source, means for holding a shoe in position to be operated upon, and means for moving said matrix toward and into engagement with the bottom of said shoe and for increasing its pressure on said shoe bottom to seal said cavity.

7. A machine for filling a cavity in the bottom of a shoe including a matrix of sufficient size to close said cavity, said matrix having a flexible margin and a rigid central portion provided with a passage for the flow of filling composition, a rod axially slideable in said passage to constitute a cut-off valve therefor, a by-pass valve adjacent said passage to control the flow of filling composition to said passage, means for holding a shoe in position to be operated upon, and means for moving the flexible margin of said matrix into firm engagement with the bottom of said shoe

and for increasing its pressure on said shoe bottom to seal said cavity.

8. A machine for filling a cavity in the bottom of a shoe including a matrix of sufficient size to close said cavity and having a passage for the flow of filling composition, a cut-off valve with its seat in approximately the plane of the matrix, means for holding a shoe in position to be operated upon, means for moving said matrix against the bottom of said shoe and into and away from a position of firm engagement in which said cavity is sealed, and mechanism to close said cut-off valve in timed relation to the operation of said moving means.

15. 9. A machine for filling a cavity in the bottom of a shoe including a matrix of sufficient size to close said cavity, said matrix having a flexible margin and a fixed central portion with a passage for the flow of filling composition, a valve with its seat approximately in the plane of said matrix, means for holding a shoe in position to be operated upon, means for moving the flexible margin into and away from engagement with the bottom of said shoe and for increasing and decreasing its pressure on said shoe bottom to temporarily seal said cavity, and means to operate said valve in timed relation with said moving means.

10. A machine for filling a cavity in the bottom of a shoe including a matrix of sufficient size to close said cavity, said matrix including a flexible working face of thin metal and a fixed central portion with a passage for the flow of filling composition, said passage having a valve with a seat approximately in the plane of said matrix, said valve comprising an axially movable rod cooperating with said seat to control said passage, a by-pass valve controlling the flow of filling composition to said passage, means for holding a shoe with its bottom up and in position to be operated upon, cam mechanism for moving said flexible working face of said matrix into firm engagement with the bottom of said shoe to seal said cavity, and mechanism to operate said cam mechanism, said by-pass valve, and said axially movable rod in timed relation.

PERCY WHITE.
